UNITED STATES PATENT OFFICE.

ARTHUR H. BRANDON, OF TOLEDO, OHIO, ASSIGNOR, BY MESNE ASSIGNMENTS, TO THE DEEP WELL ENGINEERING COMPANY, OF TOLEDO, OHIO, A CORPORATION OF OHIO.

CASING AND PIPE MACHINE.

Application filed March 21, 1922. Serial No. 545,546.

To all whom it may concern:

Be it known that I, ARTHUR H. BRANDON, a citizen of the United States of America, residing at Toledo, Lucas County, Ohio, ⁵ have invented new and useful Casing and Pipe Machines, of which the following is a specification.

This invention relates to the connecting and disconnecting of threaded lengths of ¹⁰ material, as pipe.

This invention has utility when incorporated in the assembling and disconnection of vertical lengths of pipe, as casing or tubing in deep wells or mine work, having especial ¹⁵ value in connection with the completion, preparation for use and operation of oil and gas wells.

Referring to the drawings:

Fig. 1 is a side elevation, with parts ²⁰ broken away, of an embodiment of the invention as a casing machine for gas or petroleum well operations;

Fig. 2 is a fragmentary detail view of latch operated drive shaft connector;

Fig. 3 is a side elevation of the sectional work engager or pipe gripping ring open;

Fig. 4 is a plan view of the ring of Fig. ²⁵ 3, also open;

Fig. 5 is a detail view in side elevation of ³⁰ a caster support, in lieu of the combined stirrup and anchor of Fig. 1;

Fig. 6 is a plan view of the device of Fig. 1, having instead of the stirrup anchor, the ³⁵ caster of Fig. 5, and an anchor rod or strut;

Fig. 7 is a bottom plan view of the actuator or sectional bevel gear ring, together with work guides carried thereby;

Fig. 8 is a bottom plan view, on a reduced scale of the main U-shaped frame;

Fig. 9 is a detail view of the actuator section lock;

Fig. 10 is a detail view of the actuator drive connection;

Fig. 11 is a detail view of the actuator ⁴⁵ section hinge;

Fig. 12 is a view of features of the speed changing drive;

Fig. 13 is a side elevation of the work engager and its mounting; and

Fig. 14 is a plan view of the actuator partially open.

In the instance of the use of the device of this disclosure in connection with oil or gas well operations, wherein a derrick is ⁵⁵ provided for handling the tools, there is con-

veniently at hand, without involving any installation expense, headache post 1 (Figs. 1, 6) located adjacent the well opening in the derrick floor, and sufficiently out of the way as not to seriously interfere with the ⁶⁰ usual labor operations. A slight clearance distance, say a little over two feet from the derrick floor, upon this post 1, by means of clamps 2 may be mounted eyes 3 for hinge pin 4 to swingably carry bracket 5 rigidly ⁶⁵ connected to main frame 6 of general U-form. That is, this frame has an open side. Furthermore, this frame in vertical cross-section is also here of U-form, having lower flange 7 to which is rigidly connected by ⁷⁰ bolts 8, the bracket 5. The length of the bracket 5 is such that in the swinging of this frame 6 it may come into approximate axial alignment with the well hole.

The selection of the headache post 1 as ⁷⁵ the principal locating means for this device, is for the purpose of avoiding cluttering up the derrick floor, especially in the instances where this device may be used during the drilling operations, as for placing casing. It is important to maintain the frame 6 in alignment with the well hole, when this device is in use. Anchoring means is accordingly provided. A type thereof as a fixed anchor and support is shown in Fig. 1, ⁸⁰ wherein derrick floor 9 is shown as having bolts 10 anchor plate portions 11 of upstanding eyes 12 through which may be thrust hinge pin 13 as a swing or hinge connection for depending portions 14 of flare shaped ⁸⁵ 90 brace structure 15 upwardly terminating in a pair of spaced necks 16 having heads 17. When the U-frame 6 is swung into its accurately aligned position with the well hole, the structure 15 may be swung upward from ⁹⁵ the derrick floor 9 to have the necks 16 ride into notches 18 of plate 19 fixed by bolts 20 with the lower flange 7 of the U-frame 6. There is thus simply provided a quickly detachable anchor against swinging of the ¹⁰⁰ frame 6 upon the hinge pin 4, which anchor also acts as a support against working strains up or down.

For effecting support or holding against downward strains, as well as relieving the ¹⁰⁵ hinge pin 4, the bolts 20 may attach to the lower flange 7 of the U-frame 6, depending outwardly extending bracket 21 having at its lower portion swivel pin 22 carrying (Figs. 5, 6) roller 23. This device acts as a ¹¹⁰

caster or leg for traveling over the derrick floor 9 as the frame 6 is swung upon its hinge support at the headache post 1.

This caster does not serve to hold the frame in aligned position with the well hole. A quickly detachable connection for this purpose may be effected as a truss rod structure. Between the lower flange 7 and upper flange 24 of this U-frame 6 is mounted by 10 bolts, a block carrying a radially extending headed trunnion or bearing 26 which may be engaged by hook 27 having long internally threaded sleeve portion 28 adjustably connected to the threaded end of rod 29 terminating at its remote end in eye 30 as a loose connection to corner post 31 by means of clamp 32. Accordingly this hook 27 may be adjusted by rotation as to the rod 29 for 15 locating the proper aligned position of the frame 6, and then with this hook over the trunnion 26, this frame as supported by the caster 21, 22, 23, is held against shifting. Pulling upward of the hook 27 releases the frame for quick swinging as carried by the 20 caster away from the casing and as sustained by the pin 4.

Instead of being an upward pull for unhooking as with this hook 27, the structure 15 is unhooked or released, by thrusting 30 radially outward to have the necks 16 clear the notches 18, when the U-frame 6 is clear to swing upon its hinge pin 4 away from the well hole.

With the U-frame 6 in anchored and sustained position in axial alignment above the well opening, the parts are in position for driving connection thereto. A reversible motor is provided. About gas wells it is desirable that there be no brushes for sparking with dangers incidental thereto. Dake 40 type of rotary steam engine may be used.

A prime mover 33 is shown as having its shaft 34 connected to actuate pinion 35 as a speed reduction drive in mesh with gear 36 45 on shaft 37 in frame 38. Having spline mounting on this shaft 37 are gear 39 and pinion 40 shiftable by control lever 41. Mounted in this frame 38 parallel to the shaft 37 is shaft 42 carrying gear 43 into mesh 50 with which the pinion 40 may be thrown for low speed actuation of the shaft 42, while reverse shifting brings the gear 39 into mesh with pinion 44 on the shaft 42 for high speed rotation of this shaft 42. In 55 getting pipe threads started, when they have been quite tightly connected, or have rusted in, the low speed driving through the gear 43, provides great reserve power, while after loosened up, the easier running may be 60 more rapidly handled by shifting to continue the operation of disconnecting through the pinion 44. Conversely when connecting up threaded members, the threads start easily, and may be run up quite rapidly at 65 lower power by the pinion 44. The final

tightening may occur through the gear 43, (Figs. 1, 12).

To permit conveniently locating this driving two speed gear mechanism as to the hole, and to give it a minimum weight with 70 low center of gravity against toppling over, all general features of utility in a readily portable structure as herein, the frame 38 is shown as having outward therefrom on the shaft 42 a bevel pinion 45 in mesh with 75 bevel pinion 46 on shaft 47 carried by inclined bearings 48 on the frame 38 to direct the shaft 47 toward the U-frame 6 when in working position.

The remote end of this upwardly inclined 80 shaft 47 has axial opening therein housing helical compression spring 49, normally thrusting outward therefrom latch pin or bolt 50, held in position by pin 51 in slot 52. This latch bolt 50 may be retracted by 85 lever 53 from square seat 54 having enlarged portion 55, fast with the shaft 47, (Figs. 1, 2, 10).

In effecting driving connection of this 90 shaft 47, the bolt 50 is drawn inward by the lever 53 to clear the seat 54, 55, and the shaft 47 swung upward as permitted by the universal joint 56, to embrace squared end 57 of stub shaft 58. This squared end 57 has terminal enlargement 59, so that the portions 57, 59, register respectively with the seat portions 54, 55, and the parts are held assembled against moving out of the open side of the seats 54, 55, by the bolt 50 entering axial opening 60 in the shaft 58.

This stub shaft 58 is carried in bearing member 61 connected by bolts 62 to the U-frame 6. The latch lever 53, may be retracted, when the shaft 47 is not rotating, and ready disconnection effected. This is a 105 simple means for as quickly controlling the connection and disconnection of the driving power, as is provided for the quick setting and removal of the frame 6.

Toward the U-frame 6, the stub shaft 58 110 carries a bevel pinion 63 in mesh with actuator bevel gear ring comprising major section 64 of U-form, and minor section 65. Mounted upon the upper flange 24 of the U-frame 6, is a track or bearing 66 of U-form and preferably of bronze. As this U-track or bearing registers with the U-portion of the frame 6, likewise Z-shaped upper or track completing U-shaped member 67 is held in similar registry by bolts 68 effective in assembling the track elements 67, 66, with said frame 6.

The track elements 66, 67, provide an outwardly open groove of U-extent to receive inwardly extending flange portions 69, 70, 125 of the actuator sections 64, 65, respectively. These sections 64, 65, provide an endless toothed actuator. The track portion 66 has termini 71 tapered off for proper clearance as to the shiftable section 65, but so extend- 130

ing not to preclude full registry of the section 65 therewith, (Figs. 7, 11).

Connected to the major actuator section 64 by hinge pin 72 is bracket 73 carrying the 5 minor actuator section 65. The free end of this minor or hinged actuator section 65 is provided with a narrow mouth 74 terminating in a cylindrical seat 75. The major actuator section 64, at its terminus remote 10 from the hinge pin 72, carries lock pin 76 having in the region of the mouth 74 flattened opposite sides 77, so that with the handle 78 against pin 79 (Fig. 14) the hinge section may swing into ring completing position 15 with the section 64. In this movement the mouth 74 passes the flattened sides 77 of the lock pin 76 and the pin 76 rides into the seat 75. Swinging of the handle 78 away from the pin 79 to the stop pin 80, 20 brings the flattened sides of this pin 76 out of registry with the mouth 74, and the actuator ring is locked in its annular form.

The actuator ring is shown as provided with work guide means. Radially extending 25 pairs of bolts 81 are shown as carried by the major section 64, and 82 carried by the minor section 65 (Figs. 6, 7, 14). These provide mounting means for adjustably carrying two guides 83 upon the section 64 30 and one guide 83 on the section 65. Each of these guides 83 has a slot 84 to permit of radial adjustment of transverse rollers 85 at the inner ends of these guides 83. These rollers 85 serve as anti-friction contacting 35 means for the pipe or work as passing up or down, and assist in holding the machine of this disclosure in proper aligned working position during operation. In removing tubing or casing, spiders on the derrick floor 40 may sustain and hold the pipe against rotation. In lowering casing, and some tubing, the friction in the well hole, as well as the weight of the string of pipe, may hold such from rotation. It is usual to maintain control 45 of the pipe, either by elevators or spiders. This device, accordingly, avails of this condition or these conditions in practice, and as herein shown in its simplified form, effects rotation without any additional gripping 50 features.

By omission of a second grip device, this case is a simplification over the showing in my co-pending application Ser. No. 411,573, Pipe Handling Apparatus, filed Sept. 20, 55 1920. In so far as subject-matter is shown, and not claimed in said co-pending application, this case is a continuation thereof.

The work engager is carried for rotation with the actuator. The major actuator section 64 has connected thereto by means of bolts 86, a bracket 87 carrying pin 88 eccentric to the actuator. This pin 88 is a bearing for bracket member 89 carrying transversely of the axis of the pin 88 a pivot pin

90 for link 91. This link 91 at its free end 60 has pivot pin 92 for upstanding short link 93 providing a bearing axis in the line of its upward extent for a link 94 (Figs. 4, 6, 13). This link 94 shiftable at 90° to the shifting of the link 91 connected therewith, 70 is attached to major engager section 95. This U-shaped engager section 95 has bolt 96 for detachably mounting gripping jaw 97, having parallel ribs or teeth of 90° between faces for similar effective pipe gripping in either direction of working. This 75 avoids any necessity of reversing.

The free ends of this U-shaped gripping section 95 carry pivot pins 98 respectively mounting minor engager sections 100, 101. 80 The gripping section 101 terminates, remote from its pivotal or hinge mounting, in an outwardly extending portion 102 carrying a hasp or link 103 having an eccentrically mounted pin 104 operable by a handle 105. 85 The gripping section 100, terminates in an outwardly extending portion 106, swingable into position to oppose the similar section 102 of the section 101. This portion 106 is provided with a seat 107. The sections 100, 90 101, may be swung toward each other to cooperate with the section 95 as a pipe embracing grip, to be locked into position as adjusted by set screw 108, (Figs. 3, 4.) The locking is effected by swinging the 95 hasp 103 over the portion 106, to bring the pin 104 into the seat 107. Swinging of the handle 105 radially inward, brings the eccentric pin 104 into close locking and binding 100 relation for this pipe gripping structure. 100

The compound linkage permits movement of this engager as to the actuator up and down, that is, to follow a pipe out in unthreading, or to follow a pipe down in threading. In the event the distance threaded be excessive away from the actuator, the engager may be dis-engaged and brought toward the actuator for re-engagement. Conversely, if in the following of work downward the engager comes into position 105 close upon the actuator, the engager should be disconnected from the work and re-connected away from the actuator. However, the travel distance of the engager as to the actuator is such as to take care of normal 110 threading distances. The linkage connection between the engager and the actuator, permits of slight shiftings to take care of alignment operations independently of placing such strains upon this casing handling 115 machine. However, this connection is such as to compel rotation of the engager with the actuator in either direction of actuator rotation.

For ready speeding up of pipe handling 120 operations, in addition to the quick setting up and quick removal of the machine as to the well opening, there is provided quick

control means for the engager as to positioning thereof, independently of effecting the closing thereof.

As a normal means for poising the engager and keeping it from falling through or down into the actuator, a counterweight mechanism is provided. The member 89 has a bracket extension along the direction of the link 91. This extension 109 carries fulcrum 110 for lever 112 having link connection 113 from one arm thereof with an intermediate point on the link 91. The other extremity of this lever 112 is connected by link 114 adjustable as to different openings 15 in lever 115 having its fulcrum carried by extension 116 upward from the member 89. The remote end of this lever 115 carries counterweight 117 adjustable thereon by set screw 118. Extra fitting cheeks 119 may be mounted detachably in the gripping device or engager to increase the range of sizes for use without changing to a different engager. Such changes, either by cheeks, or other size change, render desirable counterweight 25 adjustments for poising the engager. These adjustments, as shown may be taken into account by adjusting the counterweight 117 along the lever 115, or by changing the connection of the link 114 to this lever 115.

30 In down threading operations, instead of adjusting the counterweight to overbalance the engager, the counterweight may be left as a counterpoise, and supplemental lifting means provided. To this end, guide mounting bolts 81 may adjustably engage for clamping plates 120 carrying upstanding rods 121 (Figs. 1, 6, 14). Set screws 122 serve to clamp adjustably stems 123 along these two rods 121 as approximately diametrically disposed upward from the actuator. Helical tension springs 124 from the stems 123 extend to brackets 125 connected by bolts 126 to the engager. There is thus provided an automatic reset upward for the engager at once it is released from following a thread downward. The springs 124 may be adjusted by the placing of the stems 123, as to the extent of lift. The diametrical position and radial clearance of the rods 50 121 is adjusted in the placing of the plates 120 for engagement by the bolts 81.

In the operation of the machine as herein disclosed, such is mounted away from the well hole for swinging thereover, there to be locked in position and supported, by strut rod 29 and caster 21, 22, 23, or by stirrup structure 15. The drive is quickly and simply connected by bringing the seats 54, 55, to be latched by bolt 50 with the stub shaft 60 58. In swinging this machine thus into position, with one side of the various U-shaped features open, it is assumed that a length of pipe is protruding from the well hole, as handled by elevators, or by hand, and is in 65 register position with a pipe length there-

below, either for connection or disconnection, and that such length is held, either by friction on the sections therebelow in the well, or by a spider on the derrick floor. This machine in its form clears the floor of 70 the derrick adjacent the well hole, thereby allowing use of the spider or other devices.

The engager may be closed into pipe embracing position, adjusted as to the set screw 108, so that the sections 100, 101, as drawn 75 by the eccentric pin 104, snugly thrust the pipe section into biting position as to the teeth 97. The guides 83 may approximate centering of the machine as to the pipe below the engager. This adjustment of the 80 guides is effected after the actuator has been closed and locked by having the handle 78 swing against the pin or stop 80. The prime mover may now be started in the direction desired for effecting the unthreading 85 operation to the left, while for threading operation, to the right or clockwise, looking downward into the well, with right hand threaded pipe being used.

In many instances, especially in deep well 90 operations, it is desirable to thread together, or unthread some considerable lengths or strings of pipe, and then continue other drilling operations. This condition frequently arises where there are problems to 95 be met in the upper strata, especially found in the Texas field, where casing of large size is used at the surface for a depth, smaller diameter casing therebelow, and sometimes as many as three or four different diameters of such casing are used in getting the well down, drilling operations occurring between the placing of the different strings of casing. When the well is completed and the tubing is in, the several 100 casings may be taken out. Such intermittent uses as this are handled by the device of this disclosure with great speed and with no interference, so far as the set up for the other operations. The source of power in 105 such other operations may be conveniently available for the prime mover herein.

Referring to Fig. 4 the engager member 95 has the bolt 96 loosely engage the jaw 97 so that the rounded end of the link 94 as 110 the engager is swung into pulling or driving position, wedges against the back of the jaw 97 to thrust the jaw radially inward toward the pipe into more effective biting relation.

What is claimed and it is desired to secure by Letters Patent is:

1. A rotation drive device embodying a frame, a swingable support therefor, means for anchoring the frame against swinging, an actuator carried by the frame, and a work engager held to rotate with the actuator.

2. A rotation drive device embodying a frame, a carrying bracket therefor provid-

- ed with a pivotal support having its axis parallel to the axis of the device, means for anchoring the frame against swinging, an actuator carried by the frame having rotation relatively to the frame, and a work engager movable toward and from the frame and held to rotate with the actuator.
3. A rotation drive device embodying a frame, a pivotally supported bracket swingably mounting the frame, means for anchoring the frame against swinging, an actuator carried by the frame having rotation relatively to the frame, the axis of said actuator being parallel to the axis of the bracket, and a work engager movable toward and from the actuator and held to rotate with the actuator.
4. A rotation drive device embodying an open side frame, a swingable support therefor, means for anchoring the frame against swinging, an actuator ring carried by the open side frame, and a work engager held to rotate with the actuator ring and movable toward and from the actuator ring and frame.
5. A device for effecting threading up or unthreading rotation of pipe lengths in connecting up into strings or disconnecting from strings, said device embodying an open side frame, a swingable support therefor, means for anchoring the frame against swinging, a sectional actuator ring carried by the open side frame and having a section thereof movable into registry position with the frame open side, and a work engager held for driving by the actuator ring.
6. A pipe screwing device embodying a U-shaped frame provided with a track, a swingable support therefor, an actuator ring carried for rotation as to said frame track, and a work engager connected to rotate with said ring and movable axially relatively thereto.
7. A rotation drive device embodying a U-shaped frame provided with a track having a gap, and a work actuator ring carried by the track, said ring including hinged sections openable when in registry with the gap in the track to permit relative movement of work into the frame radially as to the actuator.
8. A rotation drive device embodying a U-shaped frame providing a track having a gap, a work actuator gear carried by the track, said gear including hinged toothed sections openable when in registry with the gap in the track, a drive gear for the actuator gear, a centering guide carried by the gear for directing work therethrough, and work gripping means movable axially of the gear and rotatable therewith.
9. A rotation drive device embodying a U-shaped frame providing a track having a gap, a work actuator ring gear carried by the track, said gear including a major toothed section and a minor toothed section, a hinge for connecting one end of the minor toothed section to the major toothed section, a lock for holding the other end of the minor toothed section against shifting as to the major toothed section, toothed driving means for the actuator gear, a centering guide carried by the gear for directing work therethrough, and work gripping means movable axially of the gear and rotatable therewith.
10. A rotation drive device embodying a U-shaped frame providing a track having a gap, a work actuator ring gear carried by the track, said gear including a major toothed section and a minor toothed section, a hinge for connecting one end of the minor toothed section to the major toothed section, a rotatable pin lock for holding the other end of the minor toothed section against shifting as to the major toothed section, toothed driving means for the actuator gear, a centering guide carried by the gear for directing work therethrough, and work gripping means movable axially of the gear and rotatable therewith.
11. A rotation drive device embodying a U-shaped frame providing a track having a gap, a work actuator ring gear carried by the track, said gear including a major toothed section and a minor toothed section, a hinge for connecting one end of the minor toothed section to the major toothed section, a flat sided rotatable pin lock for holding the other end of the minor toothed section against shifting as to the major toothed section, toothed driving means for the actuator gear, a centering guide carried by the gear for directing work therethrough, and work gripping means movable axially of the gear and rotatable therewith.
12. A rotation drive device embodying a U-shaped frame providing a track having a gap, a work actuator ring bevel gear carried by the track, said gear including a major toothed section and a minor toothed section, a hinge for connecting one end of the minor toothed section to the major toothed section, a lock for holding the other end of the minor toothed section against shifting as to the major toothed section, bevel pinion driving means for the actuator gear, a centering guide carried by the gear for directing work therethrough, and work gripping means movable axially of the gear and rotatable therewith.
13. A rotation drive device embodying a frame, an actuator for the frame, a disconnectable drive for the actuator, a work engager held to rotate with the actuator, and yieldable poising means for the engager as to the frame.
14. A rotation drive device embodying an open side frame, a sectional actuator carried thereby, a work engager held to rotate

- with the actuator, a drive for the actuator, a latch for disconnecting the drive and yieldable poising means for the engager as to the frame.
- 5 15. A rotation drive device embodying a U-frame, an actuator therefor embodying a U-section rotatable relatively to the frame, a work engager connected to rotate with the actuator, a disconnectable drive shaft for the actuator, and yieldable poising means for the engager as to the frame.
- 10 16. A work rotation device embodying a swingable supporting frame, a rotatable actuator having its axis parallel to the axis of swing for the frame, a work engager movable relatively to the actuator, and yieldable poising means for the engager as to the frame.
- 15 17. A work rotation device embodying a supporting frame, an actuator carried for rotation as to the frame, a work engager, a linkage connection between the engager and actuator, and yieldable poising means for the engager as to the frame.
- 20 18. A work rotation device embodying a supporting frame, an actuator carried for rotation as to the frame, a work engager, a drag link connection between the engager and actuator, and yieldable poising means for the engager as to the frame.
- 25 19. A work rotation device embodying a supporting frame, an actuator carried for rotation as to the frame, a work engager, a swivel connection between the engager and actuator, and yieldable poising means for the engager as to the frame.
- 30 20. A work rotation device embodying a supporting frame, an actuator, a work engager, and means for poising the engager as to the actuator.
- 35 21. A work rotation device embodying a supporting frame, an actuator, a work engager, and an extensible connection therebetween.
- 40 22. A work rotation device embodying a supporting frame, an actuator, a work engager, and a connection for pulling the engager to rotate with the actuator and poising the engager.
- 45 23. A work rotation device embodying a supporting frame, an actuator rotatable relatively to the frame, a work engager connected for rotation with the actuator, poising means for the engager, and means for adjusting the poising means.
- 50 24. A work rotation device embodying a supporting frame, an actuator rotatable as to said frame, a sectional ring engager connected to rotate with said actuator, and yieldable poising means for the engager as to the frame.
- 55 25. A work rotation device embodying a supporting frame, an actuator rotatably carried by said frame, and a work engager, said actuator and engager being of sectional ring form each provided with an openable side in a common radial region.
- 60 26. A work rotation device embodying a supporting frame, an actuator rotatable relatively to the frame and carried thereby, a work engager, work gripping means carried by the engager and work guiding means carried by the actuator.
- 65 27. A work rotation device embodying a supporting frame, an actuator rotatable relatively to the frame and carried thereby, a work engager, work adjustable gripping means carried by the engager and work adjustable guiding means carried by the actuator.
- 70 28. A pipe handling machine embodying an engager provided with pipe embracing means, a loose jaw, and operating connections for the engager including a member remote from the jaw movable to bring the jaw into pipe biting position.
- 75 80 In witness whereof I affix my signature.
ARTHUR H. BRANDON.
